FOLDING EASY-CHAIR

Giancarlo Piretti, Bologna, Italy, assignor to Anonima
Castelli S.p.A., Bologna, Italy

Filed Apr. 27, 1972, Ser. No. 248,345

Term of patent 14 years

Int. Cl. D6—01

U.S. Cl. D6—65

Fig. 1.

Fig. 2.

Fig. 3.

Fig. 4.

FIG. 1 is a side perspective view of the folding easy-chair of my invention;

FIG. 2 is a rear view thereof;

FIG. 3 is a side view thereof, the side not shown being identical to the side shown; and

FIG. 4 is a bottom plan view thereof.

I claim:

The ornamental design for a folding easy-chair, substantially as shown and described.
